UNITED STATES PATENT OFFICE.

HENRY M. COLLESTER, OF GARDNER, MASSACHUSETTS.

DESIGN FOR CANE FABRIC.

SPECIFICATION forming part of Design No. 26,548, dated January 19, 1897.

Application filed December 11, 1896. Serial No. 615,405. Term of patent 7 years.

To all whom it may concern:

Be it known that I, HENRY M. COLLESTER, of Gardner, in the county of Worcester and State of Massachusetts, have invented and produced a new and original Design for Cane Fabric, of which the following is a specification.

Reference is to be had to the accompanying drawing, forming a part of this specification, which shows a piece of cane fabric with my design applied.

The leading feature of my design consists of parallel stripes *a* and *b* and the intersecting stripes *c*, *a* and *c* being of a contrasting color from the body of the fabric, the stripes *a* being interrupted to show the body of the fabric within the stripes as a series of cross-shaped figures separated by the stripes *c*, the stripe *b* being arranged between the stripes *a* and appearing as a series of crosses on a background of contrasting color from the stripes *a*, one member of these crosses being formed by the stripes *c*.

f represents a piece of cane fabric bearing my design, which consists of parallel stripes *a*, arranged upon either side of the stripe *b*, and stripes *c*, intersecting the stripes *a* and *b*. The stripes *a* and *c* are of contrasting color from the body of the fabric. The stripes *a* are depressed to show the body of the fabric within the stripe as a series of cross-shaped figures separated by the stripes *c*, while the stripes *b* appear as a series of cross-shaped figures upon a background of contrasting color from the stripes *a*.

I claim—

The design for cane fabric, as herein shown and described.

In testimony whereof I have signed my name to this specification, in the presence of two subscribing witnesses, this 30th day of November, A. D. 1896.

HENRY M. COLLESTER.
